Des. 197,001
Patented Dec. 3, 1963

197,001

ADVERTISING BROCHURE DISPENSER

Martin Tashner, 299 Madison Ave., Flushing, N.Y.

Filed Mar. 18, 1963, Ser. No. 74,017

Term of patent 14 years

(Cl. D1—3)

Fig. 1

Fig. 2

Fig. 3

FIG. 1 is a front elevational view of an advertising brochure dispenser, showing my new design.

FIG. 2 is a side elevational view thereof.

FIG. 3 is a top plan view thereof.

FIG. 4 is an enlarged vertical sectional view taken on the line 4—4 of FIG. 1.

I claim:

The ornamental design for an advertising brochure dispenser, as shown.
